F. PEITER.
RUPTURE PREVENTING STRUCTURE.
APPLICATION FILED APR. 23, 1913.

Patented June 16, 1914.

UNITED STATES PATENT OFFICE.

FREDERICK PEITER, OF CLEVELAND, OHIO, ASSIGNOR TO THE GAS MACHINERY COMPANY, OF CLEVELAND, OHIO, A CORPORATION OF OHIO

RUPTURE-PREVENTING STRUCTURE.

1,099,932.

Specification of Letters Patent. Patented June 16, 1914.

Application filed April 23, 1913. Serial No. 763,155.

To all whom it may concern:

Be it known that I, FREDERICK PEITER, a citizen of the United States, resident of Cleveland, county of Cuyahoga, and State 5 of Ohio, have invented a new and useful Improvement in Rupture Preventing Structures, of which the following is a specification, the principle of the invention being herein explained and the best mode in which 10 I have contemplated applying that principle, so as to distinguish it from other inventions.

My invention relates to rupture preventing structures and particularly as applied to coking ovens or other similar devices in 15 which heat is applied, and in which the amount of contraction and expansion of the walls or parts affected by the heat varies.

The object of the invention is to provide a structure of the above described character, 20 which will be so arranged as to prevent rupturing of the parts such as would produce leakage or other deleterious results.

The said invention consists of means hereinafter fully described and particularly set 25 forth in the claims.

The annexed drawing and the following description set forth in detail certain means embodying my invention, the described means, however, constituting but one of various mechanical forms in which the principle 30 of the invention may be applied.

In said annexed drawing:—Figure 1 is a transverse section of a fragmentary portion of a coke-oven embodying my invention. Fig. 2 is a longitudinal section of said fragmentary portion of said oven, taken upon the plane indicated by line I—I in Fig. 1. Fig. 3 is a fragmentary longitudinal section taken upon the plane indicated by the line III—III in Fig. 1. Fig. 40 4 is a fragmentary horizontal section taken upon the plane indicated by line IV—IV in Fig. 1.

The illustrated structure comprises a plurality of vertical and longitudinally extending coking chambers 1 intermediately of which are located the heating or combustion-

chambers 2. These combustion-chambers communicate with fuel-ducts 3 into which the gaseous fuel is discharged through suitable nozzles 4. Suitable air-ducts 5 are provided for supplying the necessary air for combustion. In so far as concerns the above described elements, any desired or suitable structure may be adopted.

As shown in the drawing, the coking-chambers 1 extend upwardly beyond the upper ends of the heating or combustion-chambers 2. Brick walls 6 separate the coking-chambers from each other as shown 60 and extend upwardly to the top of the structure. Between these walls and above each coking-chamber is a closure-structure which consists of a lower silica-brick element 7 above which is the brick element 8 65 on top of which is the brick element 9, upon which rests the uninclosed red-brick element 10. The sides of the silica-brick element 7 are separated from the brick walls by longitudinally and vertically extending 70 spaces 11, Fig. 1, as are also the sides of the elements 8 by similarly extending spaces 12, staggered with reference to spaces 11. The red-brick element 9 is divided and the two parts separated by a longitudinally and vertically extending space 13, which, as is seen, is staggered with reference to the spaces 12. In thus staggering these elements liability of 75 leakage is reduced to a minimum. In constructing this closure-structure, sheets of paper 14 are placed between the element 10 and the element 9, between the element 9 and the element 8, and between the elements 8 and 7 as shown in Fig. 1. Similar sheets 85 15 are also placed between the element 7 and the brick wall as shown in the Fig. 1. Similar sheets 16 are also placed between the brick walls 6 and the sides of the elements 9 as shown. These sheets of paper exclude 90 the cement or mortar used in constructing the brick work and prevent the adjacent elements from adhering to each other, as will be understood. This paper burns out

after the oven is in operation and leaves these elements free to move relatively to each other, while practically in contact and making a substantially gas-tight joint. 5 That portion of the brickwork of the wall 6 above the horizontal plane of the top of the chamber is integrally united with the lower portion thereof, but is divided transversely and vertically into a plurality of 10 parts, sheets of paper 17, Fig. 4, being used during construction, as described in connection with the closure-structure to form slip-joints as in the case of the closure-structure. It will therefore be noted that the 15 wall-structure which forms the laterally inclosing walls for the closure-structure is divided into a plurality of elements which are separated from each other by transversely and vertically extending spaces. 20 During the operation of the oven and as is well understood by those skilled in the art, the variation of the degree of heat to which the parts of the structure is subjected, is such as to cause a variation in the degree 25 of expansion and contraction. Those parts near the hottest zone of course expand to the greatest degree, and this degree of expansion decreases upwardly away from this zone. The greatest amount of expansion 30 takes place longitudinally in the walls immediately adjacent to the heating or combustion-chambers. The least amount of expansion takes place in that part of the closure-structure which is closest to the outer 35 atmosphere and from which heat is therefore more readily radiated and conducted. Of the closure-structure, the element 10 expands the least, the element 9 is subjected to the next greatest amount of expansion and 40 the elements 8 and 7 then follow, the element 7 expanding most. Since these elements are all separated as shown, slip-joints are formed and this difference of expansion does not effect the integrity of the structure and 45 rupture is thus prevented. This closure-structure expands not only longitudinally but also laterally. The provision of spaces 50 11, 12 and 13 permits this lateral expansion without causing the closure-structure to bind on the wall-structure above the plane of the upper end of the coking-chambers, and therefore also permits the divisions of the said wall-structure, formed as previously 55 described, to readily move longitudinally as a result of the longitudinal expansion of the wall-structure immediately adjacent to the coking-chambers and heating-chambers, without interference from said closure-structure. Perfect freedom is therefore permitted 60 all of these parts, even under conditions of widely varying expansion and contraction and I am therefore enabled to operate an oven embodying the above described

arrangement of parts without effecting rupture and therefore without producing 65 leakage as a result of such rupture.

Having fully described my invention, what I claim and desire to secure by Letters Patent is:—

1. In a coke-oven or the like, the combination of a pair of adjacent coking-chambers; a vertical intermediate wall-structure; and a closure-structure above each such chamber and consisting of a plurality of relatively movable elements; that portion of 70 said structures lying in planes above the tops of said chambers being divided transversely into a plurality of separated parts; one element of said closure-structure being capable of yielding in a transverse direction. 80

2. In a coke-oven or the like, the combination of a pair of adjacent coking-chambers; an integral brick-work wall-structure separating said chambers; a closure-structure above each such chamber consisting of a 85 plurality of relatively movable elements; and a wall-structure, divided into a plurality of parts separated from each other transversely, and forming a lateral wall for said closure-structure; one element of the 90 latter being capable of yielding in a transverse direction.

3. In a coke-oven or the like, the combination of a pair of adjacent coking-chambers; a vertical intermediate wall-structure 95 and a closure-structure above each such chamber; that portion of said structures lying in planes above the tops of said chamber being divided transversely into a plurality of separated parts; said closure-structure being divided into a plurality of parts 100 separated from each other longitudinally.

4. In a coke-oven or the like, the combination of a pair of adjacent coking-chambers; an integral brick-work wall-structure 105 separating said chambers; a closure-structure above each such chamber; and a wall-structure united at the bottom with the top of said integral wall-structure, divided into a plurality of parts separated from each other 110 transversely; and forming a lateral wall for said closure-structure; the latter being divided into a plurality of parts separated from each other longitudinally.

5. In a coke-oven or the like, the combination of a pair of adjacent coking-chambers; an intermediate wall-structure; and a closure-structure located between the plane of the ends of said chambers and the plane of the outer corresponding extremity of the 120 oven; said wall structure forming walls for said closure-structure; the latter being disconnected from said wall-structure, whereby the latter may expand longitudinally and independently of said closure-structure. 125

6. In a coke-oven or the like, the combi-

nation of a plurality of adjacent coking-chambers; an intermediate wall-structure; and a closure-structure located between the plane of the ends of said chambers and the 5 plane of the outer corresponding extremity of the oven; said wall structure being divided into a plurality of parts separated from each other transversely and capable of

longitudinal movement independent of said closure-structure.

Signed by me, this 10th day of April 1913.

FREDERICK PEITER.
